UNITED STATES PATENT OFFICE.

CHARLES H. TREAT, OF GEORGETOWN, DELAWARE, AND ANDREW B. BANGHART, OF BALTIMORE, MARYLAND.

DESIGN FOR A DISH.

SPECIFICATION forming part of Design No. 21,583, dated May 24, 1892.

Application filed March 31, 1892. Serial No. 427,301. Term of patent 7 years.

To all whom it may concern:

Be it known that we, CHARLES H. TREAT, residing at Georgetown, in the State of Delaware, and ANDREW B. BANGHART, residing at Baltimore, in the State of Maryland, citizens of the United States, have invented a certain new Design for Pressed Wooden Dishes, of which the following is a specification.

Our invention relates to pressed wooden dishes of a new and unique design.

Figure 1 is a plan view of our design. Fig. 2 is an edge view showing the fluting and the flange. Fig. 3 is a cross-sectional view on line 2 2 of Fig. 1.

15 A is the bottom of the dish, which in shape is flat and level.

C is the flange of the dish, which is round in shape, flat, and substantially parallel with the bottom.

20 B are the sides of the dish, which are inclined and shaped at the top and bottom so as to join onto the said flange and bottom

and exhibit a double series of arcs d, which are circular in shape, sharp in outline, and of different radius. These arcs are formed by 25 the junction of a series of concavo-convex-shaped radial flutes D with the said bottom and flange.

The leading or characteristic features of the design are the concavo-convex-shaped radial 30 flutes and the sharply-outlined circular arcs of different radius at the junction of the flutes with the bottom and with the flange of the dish.

What we claim is—

35 The design for a dish, as herein shown and described.

Signed at Baltimore, in the State of Maryland, this 13th day of January, A. D. 1892.

CHARLES H. TREAT.
ANDREW B. BANGHART.
